UNITED STATES PATENT OFFICE.

ERNST WIRZ, OF BADEN, SWITZERLAND, ASSIGNOR TO AKTIENGESELLSCHAFT A. G. BROWN BOVERI & CIE., OF BADEN, SWITZERLAND, A JOINT-STOCK COMPANY OF SWITZERLAND.

ELECTRIC FURNACE.

Application filed May 14, 1927, Serial No. 191,434, and in Germany May 19, 1926.

This invention relates to electric resistor furnaces and it has among its objects the provision of a furnace of the foregoing type having improved resistor heating units adapted to be individually removed from the furnace without serious interference with the operation of the furnace.

In resistor-type furnaces that are operated on relatively low voltages, relatively rigid resistor elements are used. Accordingly, the individual resistor elements do not require complicated supporting arrangements within the furnace in order to take up the variations of the length of the elements caused by expansion or contraction under temperature changes.

It is otherwise, however, in furnaces in which the individual resistor elements are supplied from a relatively high voltage source. In such cases, the resistor elements are formed of relatively thin, flexible wire or ribbon, which does not have any inherent stiffness that would prevent it from establishing contact with the adjacent resistor elements when expanding under high temperature conditions.

According to the invention, the difficulties in providing heating units for high voltage service of the foregoing type are avoided by having the convolutions or loops forming the resistor element suspended in the furnace chamber, with a spacing member for insulatingly separating the lower ends of said loops or convolutions so arranged that such spacing member weighs upon said loops and holds the same taut. Such construction permits free expansion or shrinkage of the resistor loops, and, at the same time, effectively prevents contact between adjacent elements of said loops.

The foregoing and other features of the invention will be best understood from the following descriptions of exemplifications thereof, reference being had to the accompanying drawings wherein

Fig. 1 is a vertical sectional view through a furnace embodying one form of the invention;

Fig. 2 is an elevational view of the re-

movable side heater unit of the furnace in Fig. 1;

Fig. 3 is a view similar to Fig. 2 of a heater unit embodying another form of the invention;

Fig. 4 is a side elevational view of the heater unit in Fig. 3;

Fig. 5 is a view similar to Fig. 2 illustrating a heater unit embodying a still further modification of the invention;

Figs. 6 to 8 are fragmentary horizontal sectional views illustrating different forms of the lateral guide support of a heater unit such as shown in Fig. 5;

Fig. 9 is a view similar to Fig. 2 of still another form of the invention;

Fig. 10 is a side view of the heater unit in Fig. 9;

Fig. 11 is a top view of the floor heater unit of the furnace in Fig. 1;

Fig. 12 is a front elevational view of a laterally removable heater element of the rear wall of the furnace in Fig. 1;

Fig. 13 is a vertical sectional view through the heater unit in Fig. 12 along the line 13-13; and

Fig. 14 is a view similar to Fig. 12 illustrating a modification of the invention.

Referring to the drawings, a furnace exemplifying the invention comprises a furnace chamber 1 formed of refractory side walls 2, a floor or bottom wall 3, a roof or cover wall 4 and rear and front walls 5. The walls are formed of a suitable heat resistant material that is both an electric and heat insulator as is known in the art. In the usual constructions, the walls are made of bricks, the inner part of the walls facing the chamber being of a highly refractory fire brick or similar material.

The furnace is arranged to be heated by a plurality of heater units which are so mounted as to permit ready removal of the individual units without materially interfering with the operation of the other units or the furnace. This may be best effected by constructing the individual heater units so as to be suitable for direct parallel connection to the relatively high-voltage supply

source which is usually available without requiring series connections between the individual heater units.

As pointed out above, difficulties have been experienced in manufacturing such heater units suitable for high voltage operation on account of lack of stiffness of the relatively thin resistor ribbon which must be used in constructing the unit. These difficulties are avoided by making the heater units according to the invention as described hereinafter.

The heater units used in the furnace of Fig. 1 are of three different types—the side heater units 6 adapted to be placed along the side walls 2 in the interior of the chamber; the floor heater units 7 adapted to be placed at intervals along the floor walls 3 of the furnace chamber; and rear or front wall heater units adapted to be placed beside the rear or front walls of the chamber. These different heater units and their mounting in the furnace will now be discussed.

The side heater units 6 are each formed of a refractory supporting member 11 in the form of an elongated bar or brick of refractory material. The bar 11 fits into a suitable slot in the top wall of the furnace chamber and constitutes a part of the furnace walls. In the construction shown in the drawing, the bar 11 rests on ledges 13 of the side wall and roof, respectively, of the furnace chamber, said ledges preventing the bar from dropping down. Vertically extending through the bar 11 are two metallic supporting rods 15, said rods being suitably molded in or otherwise secured and held in fixed position in said bar. On the downwardly extending portions of the rods 15 there are mounted two transverse refractory resistor supporting plates 16 and 17, said plates having vertical perforations 18 adapted to slide over the two rods 15. The plates are provided with projections or studs 19 over which are wound a plurality of the heater loops 20 of a resistor wire or ribbon, the two ends of the ribbon being attached to the two supporting rods 15 at 21, thereby establishing a connection to the exterior of the furnace. By connecting the outer ends of the two rods 15 to the source of supply, as by means of terminal nuts 22, an electric current may be conveniently supplied to said resistor loops 20 for heating the same.

The upper supporting plate 16 is held at a fixed height within the chamber and prevented from sliding down on the supporting rods 15 by means of discs 23 welded or otherwise secured to said rods under the lower edge of the plate. The lower plate 17, however, is freely slideable on said rods, and is prevented from completely slipping down thereon by the interengagement of the projections 19 of said plates with the lower bights of the loops. Accordingly, said lower resistor plate will, by its own weight, hold

the individual loops in taut condition. Since the individual loops are joined together and constitute a single continuous strip freely slideable over the supporting projections 19, they will automatically adjust in lengths under the weight of the lower supporting plate 17 so as to maintain all the elements of the loop under substantially the same tension.

As a result, the difficulties encountered in prior art constructions on account of the changes in the length of the resistor elements with the variations of the temperature are completely eliminated. Under no conditions will adjacent loop elements come into contact with each other, or excessive tension be introduced into the structure.

In the form of invention shown in Figs. 1 and 2, the plates are provided with substantially vertical webs or ribs 27 extending into the space between the loops so as to prevent accidental contact between adjacent loop portions in case the latter should, for some unforeseen reason, become too slack and not follow the tensioning action of the lower supporting plates.

In the modification of the invention shown in Figs. 3 and 4, the heater unit comprises a block 31 extending and supported within a narrow slot at the top wall of the furnace chamber as in the construction of Figs. 1 and 2. A pair of strips 32 of a suitable refractory alloy metal have their upper ends embedded in the block 31 and serve to carry two supporting traverses 33 similar to the plate 16 in Figs. 1 and 2. The traverses 33 are each formed of a strip of refractory metal bent to form an elongated rectangular frame having its two narrow sides fitting the two downwardly extending supporting strips 32. The upper traverse 33 is suitably secured, as by welding, to the supporting strips 32 and carries a plurality of rollers 35 of insulating material over which the heater ribbon may be wound. The lower traverse 33 is freely slideable on the supporting strips 32 and also carries a plurality of rollers 35. A resistor ribbon 36 is wound on said rollers to form a plurality of heater loops, the two ends of the ribbon being connected to lead-in studs 37 extending through the bar 31 for making electrical connections to said heater ribbons 36 from outside of the furnace. As in the case of the construction in Figs. 1 and 2, the weight of the lower traverse 33 will cause self alignment of the individual resistor loops and hold said loops in taut condition.

In the foregoing constructions, a damaged heater unit may be readily removed and replaced by simply lifting the block 11 or 31 with the heater element held on the frame supported from said block, and replacing it by another similar heater unit, without interfering with the operation of the furnace.

In Figs. 5 and 6 is shown a form of the

invention wherein the removable heater unit does not constitute a relatively rigid frame as in the forms of the invention described hereinabove, but constitutes a set of loops 5 freely suspended from the removable block on the top of the furnace chamber, said loops being held in spaced relationship by a guide member or plate which is suitably supported within the furnace chamber independently 10 of the supporting members of the loop. As shown in the drawings, the removable block 31 held in the slot on the top wall of the furnace chamber, carries at its inner side a loop supporting member 41 having a plurality of projections 42 over which the resistor loops 43 may be wound. Into the lower bights of the loops extend a plurality of projections 44 of a guide plate 45 similar to the lower plate of Fig. 2, said 20 guide plate having at its two side ends engagement with suitable cooperating guiding grooves 46 on the side walls of the furnace chamber. Said side grooves may be of various shape, as shown in Figs. 7 and 8 for instance.

In Figs. 9 and 10, is shown another form of a side wall heating element. In this construction the refractory block 11 carries a pair of supporting rods 51 of refractory material. On said supporting rods are threaded a plurality of insulating blocks 52, said blocks having a central vertical perforation 53 fitting over the rod. Each block is provided with a plurality of horizontal perforations 54, extending on both sides of the vertical perforations. Within corresponding horizontal perforations of opposite blocks held on the two supporting rods 51 are mounted transversely disposed refractory tubes 55 over which a resistor wire 56 is wound in the form of a helix. A relatively large amount of resistor material may thus be accommodated within a relatively small space and by reason of the simple construction of the elements of which the heating unit is built up, heater units of different capacities may readily be manufactured and assembled. A plurality of such blocks 52 are assembled, one on top of the other, on each of the supporting rods 51, and are locked or supported in place by means of a suitable clip 56' clamped on the lower end of the supporting rods. The horizontal perforations for mounting the transverse refractory resistor elements are preferably staggered to provide favorable heat radiating conditions within the furnace chamber.

The floor heater element 7 of Fig. 1, referred to, a plan view of which is shown in Fig. 11, is also of the removable unit type. It comprises a block 61 of refractory material fitting into a suitable slot in the side wall of the furnace chamber and thus constituting in itself a portion of said side wall. Within the side block are embedded a pair

of supporting rods 62 to which are secured a plurality of transverse supporting members 63 bracing said rods and constituting in conjunction therewith and the block, a rigid frame. The lower ends of said transverse supporting members 63 constitute leg projections 64 adapted to rest against the floor of the furnace chamber. At the upper ends said supporting elements constitute transverse plates having perforations 65 for receiving a series of refractory insulating tubes 66 over which a resistor wire is wound in the form of a helix. The individual resistor units 66 are suitably interconnected to two terminal studs 67 extending through the side block for making external connections to said resistor elements. The entire heating unit may be readily withdrawn for replacement or repair without interfering with other elements of the furnace. A similar construction may also be used as a heater unit on the roof wall of the furnace chamber.

A construction of the type utilized in the floor heater element of Figs. 1 and 11 may also be utilized for heater units that are to extend vertically inside the chamber, but which are not to be suspended from the roof wall thereof. A construction of such character is shown in Figs. 12 and 13, as applied to a heater unit mounted in front of the rear wall of the furnace in Fig. 1. On a refractory block 71 that is slidably supported in a transverse slot 72 on the floor of the furnace chamber, near the rear wall 5, there are mounted a pair of spaced upstanding supporting bars 73, said bars being secured to said block by means of bolts 74 which also serve as external connections to the resistor elements. The opposite walls of the bars 73 are provided with perforations 75 for receiving refractory tubes 76 over which is wound a helical resistor wire 77 for heating the furnace. With such construction a portion of the side wall of the furnace corresponding to the width of the heater unit, must be made removable as shown at 78, in order to permit the passage of the frame carrying the resistor elements. A suitable duct 79 underneath the supporting block 71 is provided for the electrical connections to the resistor elements.

In the form of the invention shown in Fig. 14, a resistor structure of the type shown in Figs. 3 and 4 is supported on a frame unit of the type utilized in the floor heating unit of Figs. 1 and 11. From a vertical supporting block 81 of refractory material removably mounted within a slot in a side wall of the furnace chamber, there extend a plurality of horizontal supporting rods 82 of refractory metal. Said supporting rods 82 carry in turn a plurality of transverse bars or bracing members 83 constituting in conjunction with said block 81 a unitary

frame. Between opposite sides of the bars 83 are mounted traverses 85 for supporting a plurality of resistor loops as described above.

5 The foregoing constructions permit the removal of the heating units either from the top or from the sides or from the bottom of the furnace chamber. The choice of particular construction of the heating units will 10 depend on the particular conditions for which the furnace is built. For example, when a number of furnaces are to be arranged side by side, heater units that are to be removed from above or from below are 15 used. Where the furnace chambers are built one above the other, the heater units are built for lateral removal.

In each of the various types of heating 20 units, the self-tensioning arrangement of the units illustrated in Figs. 1 to 8 may be employed, securing the advantageous features of this construction independently of the direction in which the unit is adapted to be removed from the furnace.

25 Many other modifications will suggest themselves to those skilled in the art, and it is accordingly desired that the appended claims be given a broad construction.

I claim:

30 1. An electric resistor heater comprising a continuous resistor heating element wound into a plurality of loops, a pair of spaced supporting members engaging the opposite bights of said loops, said loops being loosely 35 mounted on said members and held stretched thereby, and guide rods engaging said members to permit sliding movement of one of said members with respect to the other.

2. In an electric resistor furnace having 40 a plurality of refractory walls enclosing a furnace chamber, a heater comprising a refractory block removably mounted in a slot on the wall of said chamber, a pair of supporting rods secured to said block and extending into said chamber, a pair of transverse members mounted on said rods, one of said members being slidable thereon, a resistor wire wound between said transverse members to form a plurality of loops having 45 their bights supported by said members, said heater being so mounted within said chamber that the slidable loop-supporting member weighs on said loops and holds the same in stretched condition.

50 3. An electric resistor furnace having a plurality of refractory walls enclosing a furnace chamber, a heater unit comprising a refractory block mounted in a slot on the top wall of said chamber and constituting a portion of said wall directly communicating 55 with the interior of the chamber, a heater wire wound into a plurality of loops suspended from said block into the interior of said chamber, a refractory insulating member spacing the lower bights of said loops

and weighing thereon to hold said loops in taut condition.

4. An electric resistor furnace having a plurality of refractory walls enclosing a furnace chamber, a heater unit comprising a refractory block mounted in a slot on the top wall of said chamber and constituting a portion of said wall directly communicating with the interior of the chamber, a heater wire wound into a plurality of loops suspended from said block into the interior of said chamber, a refractory insulating member spacing the lower bights of said loops and weighing thereon to hold said loops in taut condition, and means for guiding said member in definite relationship to said block. 70

5. An electric resistor furnace having a plurality of refractory walls enclosing a furnace chamber, a heater unit comprising a refractory block mounted in a slot on the top wall of said chamber and constituting a portion of said wall directly communicating with the interior of the chamber, a heater wire wound into a plurality of loops suspended from said block into the interior of said chamber, a refractory insulating member spacing the lower bights of said loops and weighing thereon to hold said loops in taut condition, and means for guiding said member in definite relationship to said block. 80

6. An electric resistor furnace having a plurality of refractory walls enclosing a furnace chamber, a heater unit comprising a refractory block mounted in a slot on the top wall of said chamber and constituting a portion of said wall directly communicating with the interior of the chamber, a heater wire wound into a plurality of loops suspended from said block into the interior of said chamber, a refractory insulating member spacing the lower bights of said loops and weighing thereon to hold said loops in taut condition, and guide rods extending from said block for guiding said tensioning member relatively thereto. 90

6. In an electric resistor furnace having a plurality of refractory walls enclosing a furnace chamber, a heater unit comprising a relatively narrow block of refractory insulating material removably mounted in a slot of said wall and constituting a part of the enclosure of said chamber, a pair of refractory metallic supporting rods mounted on said block and extending into said chamber 100 from the exterior of the furnace, a transverse supporting member extending between said supporting rods and constituting in conjunction therewith and with said block a unitary frame removable from said furnace through said slot, and a resistor wire mounted on said frame, said resistor wire having its ends connected to said rods for receiving current from the exterior of said furnace. 110

7. In an electric furnace, a heating unit 115 extending into and removably associated with the same; said unit including a block forming part of and having a free fit with respect to a wall of said furnace for movement outwardly away from said wall, a plurality of elements supported within said furnace and associated with said block for such movement therewith and spaced and arranged to form a row, a plurality of elements disposed within said furnace below 120 said first-named elements and spaced and arranged to form a lower row complementary to the upper row, and a resistor member extending from one end to the other of said rows and alternately around the op- 130

positely-disposed and respective elements of the upper and lower rows to form vertically-disposed loops providing a suspending support for the lower elements from the upper elements such as to permit of relative vertical movement of the upper and lower elements with respect to each other consequent

to expanding and contracting action of said resistor member.

In testimony whereof I have hereunto 10
subscribed my name at Zurich, Switzerland,
this 2nd day of May, A. D. 1927.

ERNST WIRZ.
